(57) **CLAIM**

The ornamental design of an access floor module, as shown and described.

DESCRIPTION

FIG. 1 is a top perspective view of access floor module showing the new design;

FIG. 2 is a bottom perspective view thereof;

FIG. 3 is a top plan view thereof;

FIG. 4 is a front elevational view thereof;

FIG. 5 is an elevational view of the right side thereof with the left side being a mirror image;

FIG. 6 is an elevational view of the rear side thereof; and,

FIG. 7 is an elevational view of the bottom thereof.

The features in the drawings shown in broken lines form no part of the claimed invention.
